8 Claims. (Cl. 78—48)

This invention relates to combination riveting tongs and punch pliers which may be utilized in riveting, perforating, punching, spot welding and the like.

According to the invention, the combination comprises a tool and a counter tool, a rod for causing the tool and the counter tool to draw nearer to or away from each other, movable means for moving the rod, and means which permit the tool and the counter tool to draw nearer to or away from each other without moving the means for moving the rod. To move the tool or counter tool or both the handles of the tongs need therefore to be compressed only for the actual pressing work, while the application of the tongs and the approach of the tool or counter tool to the work do not require any motion of the legs of the tongs, so that the entire travel of the legs can be utilized for actual work and a favorable conversion of energy obtained.

The combination tongs are so constructed that the rod moving the tool or counter tool is guided in a tube at one end of which the tool and counter tool are provided. This tube serves as leg, and a second leg is articulated to a part disposed in the tube.

The invention further contemplates the formation of the tongs so that it is convenient to handle and the center of gravity thereof is as much as possible located in one hand. For this reason the second leg is articulated to the end of the tube that is opposite to the tool and counter tool, and the second leg can be turned 360° about the axis of the first leg.

To make possible the use of the driving device of the tongs for tongs with differently constructed tools and counter tools, in which case the rod transmitting motion sometimes has to exert pressure and sometimes has to pull, the legs and the rod are joined by a crankshaft the pin of which is adjustable in such manner that during compression of the legs the rod exerts either pressure or pull.

The object of the invention, to cause the tool and the counter tool to draw nearer to or away from each other without any motion of the legs of the tongs, can be attained in various ways, for example by rendering the rod moving the tool displaceable in its axis by relative displacement of the two legs or parts thereof and fixable in end positions. This can be effected by a bayonet joint arranged at that end of the leg which carries the tool and the counter tool located opposite these tools so as to insure the proper position of the center of gravity of the tongs.

The working axis of the tool and counter tool need not coincide with the axis of the rod moving these two members. Both axes may for instance extend parallel to one another.

Another object of the invention is to construct the tongs so that they can also be motor

driven, and for this purpose the second leg of the tongs is articulated to the piston rod of a motor, such as a compressed air motor.

Still another object of the invention is to construct the compressed air motor in such manner that it is particularly adapted for handling the tongs.

The second way to cause the tool and counter tool to draw nearer to and away from one another without involving motion of the legs of the tongs consists in bringing the tool nearer to the counter tool or farther away from it by swinging it about an axis parallel to the working axis, though the arrangement may be such that both the tool and the counter tool can be swung about this axis to facilitate the application of the tongs.

It may be stated that tools in accordance with the present invention can be used in connection with many different types of machines and constructions as for instance in the construction of airplanes and in the construction of frameworks of all kinds.

By way of example, three embodiments of the invention are illustrated in the accompanying drawings, in which

Figures 1 to 4 show a construction, wherein the legs of the tongs are manually actuated, the working axis being disposed parallel to the axis of the rod moving the tool and both the tool and the counter tool may be swung about an axis extending parallel to the working axis and the axis of the rod.

More particularly:

Fig. 1 is a view, partly in section, of the leg portion of the tongs;

Figs. 1b and 1c are cross-sectional views taken on lines Ib—Ib and Ic—Ic respectively of Fig. 1;

Figs. 2 and 3 are cross sections taken on the lines II—II and III—III, of Fig. 1; and

Fig. 4 is a side view, partly in section, of the head portion of the tongs;

Figs. 5 to 10 illustrate a modification, in which the tongs are driven by a compressed air motor.

More particularly:

Fig. 5 is an elevation; Fig. 6, a longitudinal section thereof;

Fig. 7, a cross section taken on the line VII—VII, of Fig. 6, but with the rotary valve in a different position; Fig. 8, a horizontal section of a part of Fig. 6 taken on line VIII—VIII thereof, Fig. 9, a horizontal section of the tongs taken on line IX—IX of Fig. 10; and Fig. 10 an end view of this type of tongs;

Figs. 11 to 15 illustrate a third modification, in which the tool is swingable relative to the counter tool and both tools can be swung relative to their holder.

More particularly:

Fig. 11 is a section of the head portion of the tongs;

Fig. 12, a view of the rear portion of the tongs;
Fig. 13, a section of the head portion taken on the line XIII—XIII, of Fig. 11;

Fig. 14, a section of the head portion of the tongs on the line XIV—XIV, of Fig. 11;

Fig. 15 is a side view of the head portion of this type of tongs.

Figs. 16 and 17 are cross sections of the projection 54, showing the various slots.

Referring to the drawings, and first to Figs. 1 to 4, the tongs comprises a substantially tubular leg 1 at one end of which the tool 2 and the counter tool 3 are arranged while to the other end thereof the second leg 4 is articulated. The parts by means of which the second leg 4 is articulated to the first leg 1 are disposed in a fork whose sides 5 are formed of parallel plates and have circular openings 6 which are closed by the covers 8 secured by screws 7. In the covers 8 a crankshaft is arranged by means of its coaxial pins 9. The crank members 11 or webs carrying the crank pin 10 are square. The second leg 4 is also provided at its end with a fork whose sides 12 are formed of plates disposed parallel to one another. The plates are spaced similar to the square crank members 11 and possess corresponding openings for the insertion of these members. In this way the leg 4 is articulated to the leg 1 in such manner that the crankshaft 13 engaging the crank pin 10 may be subjected to a pull or pressure according to how the squares 11 are inserted in the sides 12 of the second leg 4. At the end engaging the crank pin 10 the crankshaft 13 is shaped somewhat like a horseshoe, and the pin 10 is embraced by an inserted piece 14 which is connected with the crankshaft by a conical pin 15 or some other suitable means. The other end of the crankshaft 13 is articulated to a fork possessing two sides 17 which are secured to a cylindrical member 18 forming the shank of the fork and being the end of a rod 19 passing through the tubular leg 1.

The shank of the fork members 5 is formed by the bayonet sleeve 20 which is placed over the adjacent end of the leg of the tongs. The bayonet sleeve 20 has two oppositely disposed longitudinal slots 21 and at the end opposite the fork members 5 is provided with cross slots 22. In these slots noses 23 are guided which are arranged on the tubular leg 1 at the end thereof opposite the tool and counter tool. The leg 1 is rotatably disposed in the bayonet sleeve 20, corresponding to the bayonet joint, and over the sleeve 20 an additional sleeve 24 is placed which is secured thereto by a screw 25 and in its inner portion has a collar 26, the sleeve 24 being so arranged relative to the sleeve 20 that the collar 26 covers the bayonet slots 21 and 22. The collar 26 is provided with longitudinal slots 27 which are preferably staggered 90° relative to the bayonet slots 21 and which are for the purpose of bringing the sleeve 20 over and beyond the noses 23 on the tube 1.

At the end of the leg 1 opposite the fork 5 a holder 28 is connected by a special means permitting turning of the second leg 4 about the axis of the first leg 1 to an extent of 360°. The end of the leg 1 facing the holder 28 is therefore fitted with a collar 29 and with a connecting bushlike member 30 provided with a thread 31 adjacent to the collar 29. Near the collar 29 the thread 31 is in engagement with a tube 32, also threaded at the corresponding end, in which the bushlike member 30 is positioned as a guide. The tube 32 serving as handle is disposed on a cylind-

rical projection 34 of the holder 28 and at its end has a collar 33 which is adjacent to a collar 35 of the cylindrical projection 34 and is rotatably held by a nut 36 screwed upon the threaded collar 35. The rod for moving the tool is subdivided and comprises the members 19 and 37 which at their abutting ends are provided with collars 38 maintained together by two half bushes 39 which in turn are held together by their fitting in the tubular leg 1.

In the construction shown, the working axis A—A is staggered relative to the axis of the rod 19, 37, and the tool 2 and the counter tool 3 are rotatably and fixedly arranged about an axis B—B which is parallel to the working axis A—A and the axis of the rod 19, 37. For this purpose both the tool 2 and the counter tool 3 are secured to intermediate members 40, 41, the member 40 carrying the tool 2 being connected with the motion transmitting rod 37 by a thread 42 and being guided with its shank 43 in the counter tool carrying member 41 which is connected with the holder 28 and has a sleeve-like shank 44. Rotation and fixing of the tool and counter tool can be effected by threaded pins 45 coaxially arranged on both the tool 2 and the counter tool 3, which are positioned in corresponding bores of the intermediate members 40, 41 and can be tightened by nuts 46. The tool 2 is also guided with its shank 47 in a sleeve-like shank 48 of the counter tool 3.

The tongs described function as follows:

Owing to the spreading of the legs 4 and 1, pressure is brought to bear upon the rod 19 and the rod 37 by means of the crankshaft and the tool 2 drawn away from the counter tool 3, so that the mouth of the tongs is open. During this motion, the left hand embraces the handle 32 and the leg 1 to prevent relative motion thereof and the right hand embraces the handle, not shown, of the second leg 4. By slightly turning the leg 4 about the axis of the rod 19 the bayonet sleeve 20 connected with the fork 5 is moved to such an extent that the noses 23 emerge from the cross slots 22 and enter the longitudinal slots 21, whereupon the tubular leg 1 is inserted in the bayonet sleeve 20 until the noses 23 arrive at the end of the sleeve adjacent to the fork members 5. The counter tool 3 is thus farther removed from the tool 2, and the tongs can now be applied to the work. To bring the tool 2 and the counter tool 3 together again to such an extent that only the distance involving pressure has to be negotiated the leg 1 is withdrawn from the sleeve 20 until the noses 23 can be locked in the cross slots 22 by a slight turn of the bayonet sleeve 20. The actual pressure operation can now begin by the compression of the legs 1 and 4. Obviously by giving up the arrangement that the tool and the anvil can be displaced about an axis parallel to the working axis and to the axis of the rod for operating the tool, the tool and the anvil take the places of the intermediate members 40 and 41, and are suitably modified at their shaft.

A pair of tongs operated by a compressed air motor is shown in Figs. 5 to 10.

To the tubular leg 49 of the tongs a stirrup working head 51 carrying the counter tool 52 is attached by means of a nut 50. The leg 49 is indirectly connected with the casing 53 of the compressed air device, and the casing 53 is provided with a cylindrical projection 54 into which the bayonet sleeve 59 is screwed by means of the thread 60. The sleeve 59 has longitudinal slots

58 and cross slots 61 which are staggered 180° relative to each other. At the end where the leg 49 is introduced into the cylindrical projection 54 a bush 55 having inner longitudinal grooves 56 staggered 180° is screwed in in such manner that the longitudinal grooves are staggered 90° relative to the longitudinal slots 58 of the bayonet sleeve 59. The bush 55 is held in position by a screw 57. The tubular leg 49 supports the two noses 62 staggered 180°.

This construction also thus affords the possibility of displacing the leg 49 and the counter tool 52 in the direction of the axis of the leg and locking them without moving the leg of the tongs. The arrangement could of course also be such that the tool is moved by means of the bayonet joint without actuation of the leg of the tongs and that the counter toll remains in unchanged position or that both are moved. The tool 52, as seen from Fig. 5 is fixedly attached to the tubular leg 49. From Fig. 6, it will be seen that on the leg 49 there are mounted the bayonet lugs 62, which can be moved in the bayonet slot 58, 61. Thus by withdrawing the leg 49 from the sleeve 59, the lugs 62 sliding in the bayonet slot 58, the tool 52 is moved away from the tool 79, and by inserting the lugs 62 in the slot 61, is locked. Similarly the opposite movement is possible at the end of which the lugs 62 are locked in the transverse slot 61.

The cylindrical projection 54 connects with the crankcase which is integral with the bayonet sleeve 59 and consists of a fork having side pieces 63 in the form of parallel plates. The side members 63 have circular and coaxial bores 64 which are closed outside by the covers 65 secured by the screws 66. In the covers 65 a crankshaft with coaxial pins 67 is arranged and provided with the crank pin 68 whilst the crank members 69 being squares. The connecting rod 70 engaging the crank is divided in the longitudinal direction, and the two parts are connected by the screws 71. At both ends a fork is formed whose sides are formed also of parallel plates 72, 73. The sides 73 which engage the crankshaft have coaxial square clearances into which the square crank members 69 fit. When the connecting rod 70 is moved, the crankshaft is also turned. The crank pin 68 is joined, at 75 by means of a crank rod 74, to a fork 76 whose shank 77 is connected with a rodlike member 78 by being screw threaded into the tubular rodlike member 79 which in turn is connected with the tool 79.

According to the construction of the tool and counter tool, the performance of the work to be done by the tongs requires the exertion of a pull or a pressure upon the rodlike member 78 in the axial direction thereof. This can be easily done by staggering the squares 69 180°. If this arrangement is not desired, a crank pin may be inserted between the fork members 73 of the connecting rod 70 and the members may be provided on their outside with coaxially disposed pins.

The connecting rod 70 is at 79 articulated to a piston rod 80 which at 81 is articulated to the piston 82 which is of the usual construction. The piston 82 can move in the cylinder 84 formed by the casing 53 and fitted with a liner 83. The compressed air part 85 of the cylinder 84 is supplied with air by means of a small piston rod 88 firmly connected with the piston 82, for instance by a thread 86, and provided with a bore 87. At the end of the piston rod 88 oppo-

site to the piston 82 a piston 89 is secured by a perforated screw 90, which moves in an auxiliary cylinder 92 having a liner 91 and being arranged in the control casing 93 in such manner that its axis lies in the vertical plane of symmetry of the casings 53 and 93. The return of the piston 82 is effected by two piston rods 95 which are preferably symmetrically arranged relative to the vertical sectional plane of the cylinder 84, surrounded by distance pieces 94 and connected with the piston 82 by the thread 96. At the end of the piston rod 95 opposite the piston 82 smaller pistons 97 are secured which move in auxiliary cylinders 99 provided with liners 98.

Compressed air is supplied through a hose connection 100 which is screwed into the control casing 93 by means of a threaded pin 101. The connection 100 has a bore 102 communicating at one end through radial bores 103 with an annular space 104 formed by an annular groove of the connection 100 and a sleeve 106 drawn over the threaded pin 101 and the adjacent end of the connection 100 with an interposed packing 105. The sleeve 106 forms a collar 107 abutting with an interposed packing 108 against the front side of the control casing 93 and is provided a sleeve-like continuation 109 which serves as a second handle for the tongs and also as a handle for controlling the sleeve 106 acting as a rotary slide valve. Within the sleeve 109 the connection 100 is provided with a packing 110 and a stuffing box gland 111 in the form of a spring plate which supports a compression spring 112 also supported by a collar 113 of the connection 100, which closes the bore of the sleeve 109. The collar 113 connects with a hexagon nut 114 for screwing in the connection.

The rotatable shaft 106 is surrounded by another bushing 115 disposed in a corresponding bore of the control casing 93. From the auxiliary cylinders 92 as well as from the auxiliary cylinders 99 bores 116, 117 pass through the control casing 93 to the stationary sleeve 115 which, as continuations of these bores, is provided with the radial bores 118. The bores 116, 117 are preferably so arranged in the casing 93 that the bores 117 establishing communication with the auxiliary cylinders 99 open on the horizontal sectional plane into the sleeve while the bore 116 establishing communication with the auxiliary cylinder 92 opens on the vertical sectional plane into the sleeve 115.

In the controlling member 106 of the rotary slide valve the arrangement is as follows in the position shown in Fig. 6: On a plane extending vertically to the axis of the sleeve a radial bore 119 is disposed and, staggered 90° in both directions relative thereto, clearances 120 being provided on the surface of the sleeve, which extend a distance parallel to the axis of the sleeve. Furthermore, a clearance 121 and radial bores 122 are similarly arranged and staggered at the angle at which the rotary slide has to be turned for controlling action, the radial bores 122 being staggered 90° in both directions. The plane mentioned coincides with the plane on which the radial bores of the sleeve 115 are disposed. At a distance from this plane VII—VII on which the axes of the bores 119 and 122 are positioned, in the direction of the side of the casing 93 facing the sleeve 109, and lying with their bores on a plane parallel to the plane VII—VII, bores are provided in the casing 93 and the sleeve 115 thereof, which comprise a bore 123 disposed with

its axis in the vertical sectional plane and the bores 124 whose axes lie in the horizontal sectional plane. The clearances 120 now extend far enough that at a corresponding adjustment of the rotary slide valve 106, 109 they can connect the bores 117 with the bores 124, and the clearance 121 has such an extent that at a corresponding position of the valve it can connect the bore 116 with the bore 123.

The mode of operation of the rotary slide valve is as follows:

In the position shown in Fig. 6 the compressed air passes through the bore 102, the radial bore 103, the annular space 104, the bores 119, 118 and 116, the cylinder 92 and the bore 87 to the pressure side 85 of the cylinder 84, exerts pressure upon the piston 82 and thus drives the pistons 97 into the cylinders 99. The air contained in the cylinders 99 escapes through the channels 117, the bores 118, the clearance 120 and the bores 124.

For returning the piston 82, after rotation of the control sleeve 103, the air, as shown in Fig. 7, passes out of the annular space 104 through the bores 122, 118 and 117 into the cylinders 99 where it pushes out the pistons 97 and thus also moves the piston 82. The pressure side 85 of the cylinder 84 is emptied by the bore 87 of the piston rod 88, the cylinder 92, the bores 116 and 118, the clearance 121 and the bore 123. Some bores may be omitted if both cylinders 99 are united by a bore 125.

Tongs, in which the relative displacements of their legs or parts thereof is also to be effected by compressed air, are preferably provided with an auxiliary cylinder that is not in operative connection with the main piston 82 and have auxiliary cylinder pistons, the air passages of which can be controlled by a rotary slide valve while utilizing the motion of the leg 49 relative to the casing 54.

In the construction according to Figs. 11 to 15 the tool and the counter tool can also be drawn nearer to or away from one another without any motion of the legs of the tongs by providing for relative motion of the tools. The two legs 126 and 127 are articulated to one another, and one end of the leg 126 has a holder for the tool 128 and the counter tool 129, which comprises a fork having sides 130 formed of parallel discs and having a cylindrical body 131 attached to the side opposite the leg 126 a cylindrical body 131. On the cylindrical body 131 the shank 132 of the tool 128 is provided which is connected with the shank by an arm 133, the shank 132 being cylindrical on the outside and having a cylindrical clearance on the inside. Over the shank 132 of the tool is placed the shank 134 of the counter tool 129 which is connected with this shank by an arm 135. The shank 134 is provided with a cylindrical bore.

In the construction shown the tool 128 is swingably disposed relative to the counter tool 129, and both tools are movable relative to the holder 130 and particularly its cylindrical projection 131 about the joint axis of the concentric cylinders extending parallel to the working axis A—B. The cylindrical shank 134 of the counter tool 129 has a slot 136 which is large enough to permit motion of the tool arm 133 within the range of the pressure work to be accomplished. This slot 136 is symmetrically arranged to the surface line of the shank 134 of the counter tool 129 nearest to the working axis A—B and extends toward the side opposite the holder 130 into steps 137 75

along which the tool arm 133 can move when the tool 128 is swung out.

As a feeler for the return of the tool into operative position a cylindrical bore 139 extending in radial direction is further provided in the bottom 138 of the shank 134 and accommodates a compression spring 140 and a ball 141 which partly enters a channel 142 disposed vertically to the cylinder axis in the bore of the shank 134.

10 As shown particularly in Fig. 14, the cylindrical projection 131 at the point where it is attached to the fork members 130 has a collar 144 provided with radially arranged teeth 143 which are in adjustable engagement with notches 145 correspondingly arranged in the bore of the shank 134 of the counter tool 129 for jointly stopping the tool and counter tool relative to the cylindrical projection 131 of the holder 130.

Fig. 14 shows a small space between the teeth 20 and the notches for the sake of clearness, though the parts actually fit of course into one another.

The cylindrical projection 131 of the holder 130, through the bottom 145 of which the rod 146 moving the tool 128 passes, has a cylindrical clearance 147 which opens towards the bottom 138 of the tool shank 134 and in which a compression spring 148, surrounding the rod 146, is disposed, which is supported by the bottom 145 of the clearance 147 and also by the bottom 138 of the tool shank 134. On the end of the rod 146 provided with thread 149 and passing also through the bottom 138 of the tool shaft 132 an adjusting nut 151 is arranged in a clearance 150 of the tool for bringing the tool 128 nearer to or away from the counter tool, according to the different work pieces to be handled, and for fully utilizing the stroke. The cylindrical clearance 147 preferably contains a sleeve 152 surrounding the rod 146 for guiding the spring 148.

40 The rod 146 for moving the tool is articulated at 153 to a bell crank 155 articulated between the fork members 130 at 154 and having forked ends 156 and 157. To the fork 157 another rod 159 is articulated at 158 which is guided in the leg 126 of the tongs, which is provided, in addition to the holder members 130, with a sleeve 160 serving as a handle. The rod 159 is coupled with a rod 161 which at one end possesses a fork 162 to which at 163 a crank rod 164 is articulated which is also articulated to the crank pin 165 of a crankshaft. The coaxial pins 166 of the crankshaft are arranged in the covers 167 of a forklike casing 168 which with a cylindrical shank 169 is positioned on the end of the leg 126 opposite to the holder 130. The sides of the forklike casing 168 are formed of parallel plates having circular openings which are covered by the members 167 secured by the screws 170. The side pieces of the crankshaft are formed as squares 171. The second leg 127 is articulated to the crankshaft by having its end 172 made into a fork comprising two parallel plates. These plates are parallel with the covers 167 and have square clearances into which the square members 171 of the crankshaft fit.

The arrangement is further such that the leg 127 can be swung 360° about the axis of the rod 159, 169 to facilitate the application of the tongs. For this purpose the rod guided in the leg 126 is divided into the parts 159 and 161 which at their abutting ends possess the collars 173 and which are kept together by a two-part sleeve 174 surrounding the collars which are held in position by the leg 126. In view of the fact that owing to its articulation to the bell crank 155

the rod 159 is not displaced exactly in axial direction some play is allowed between the connecting rod portion and the sleeve 174.

The device shown in Figs. 11 to 15 operates as follows:

In the position shown the tongs are closed. When the legs 126 and 127 are spread apart, the tool 128 is drawn away from the counter tool 129 and guided in the slot 136 until it emerges therefrom. The tool can then be swung so that its arm 133 can be moved along one of the two steps 131. After introduction of the work, i. e., after application of the tongs, the tool is swung back and can be adjusted by the nut 151 so as to accurately rest on the work. Pressure can then be exerted by compressing the legs.

In the example shown the rod 146 moving the tool is rectangularly positioned relative to the subdivided rod 159, 161 guided in the leg 126, though the arrangement may of course be such if desired that the rod 146 forming the axis of rotation is positioned at a different angle to the axis of the rod 159, 161 or is coaxial therewith.

The construction shown permits relative motion not only between the tool and counter tool but also between the tools and the holder, whereby application of the tongs can be greatly facilitated. This is effected by depressing the tool 128 and the counter tool 129 together with their shanks 132 and 134 against the action of the spring 148 in such manner that the teeth 143 come out of engagement with the notches 145, whereupon relative motion to the desired degree is carried out, so that after return of the tool and counter tool in upward direction the teeth 143 come into engagement again with other notches 145.

I claim:

1. A punching or riveting tool of the kind referred to, comprising a pair of jaws, a tubular member at one end of which the jaws are supported for relative movement, a rod guided within said tubular member and connected to one of said jaws, a housing movably engaged by the other end of said tubular member, means in said housing for actuating the rod to move said jaw relative to the other jaw, and a coupling arranged between said tubular member and said housing and which is dislocatable to permit relative movement of said jaws towards and away from each other independently of the actuation of said rod, said tubular member and actuating means being manipulatable to engage and disengage said coupling and to hold and operate the tool.

2. A tool according to claim 1, in which the coupling includes a sleeve extending from said housing and having circumferential and longitudinal bayonet slots therein said sleeve surrounding the end of the tubular member which is formed with abutments co-operating with the bayonet slots, said tubular member being rotatable within the sleeve to cause the abutments to disengage from the circumferential bayonet slots and enter the longitudinal slots whereby the tubular member may be axially moved within the sleeve, and in which a collar is provided closing the open ends of the bayonet slots so that the tubular member is normally prevented from being withdrawn from the sleeve by the other.

3. A punching or riveting tool according to claim 1 in which the rod actuating means include a crank journalled in the housing said crank having square webs and a crank pin connected to the rod, and a lever pivoted co-axially with the

crank in said housing and having square apertures engaging said square webs whereby said lever can rotate said crank.

4. A punching or riveting tool according to claim 1 in which the rod actuating means include a crank journalled in the housing, said crank having square webs and a crank pin connected to the rod, and a lever pivoted co-axially with the crank in said housing and having square apertures engaging said square webs whereby said lever can rotate said crank, and in which the rod is formed in two co-axially connected parts of which the part connected to the crank pin is angularly rotatable relatively to the other part.

5. A punching or riveting tool of the kind referred to, comprising a pair of jaws, a tubular member at one end of which the jaws are supported for relative movement, a rod guided within said tubular member and connected to one of said jaws, a housing movably engaged by the other end of said tubular member, means in said housing for actuating the rod to move said jaw relative to the other jaw, a coupling arranged between said tubular member and said housing and which is dislocatable to permit relative movement of said jaws towards and away from each other independently of the actuation of said rod, telescoping shafts carried by said jaws the common axis of said shafts being parallel to and offset from the axis of the tubular member and said shaft, and co-operating tool members carried by said shafts.

6. A punching or riveting tool of the kind referred to, comprising a pair of jaws, a tubular member at one end of which the jaws are supported for relative movement, a rod guided within said tubular member and connected to one of said jaws, a housing movably engaged by the other end of said tubular member, means in said housing for actuating the rod to move said jaw relative to the other jaw, a coupling arranged between said tubular member and said housing and which is dislocatable to permit relative movement of said jaws towards and away from each other independently of the actuation of said rod, a lever pivoted in said housing and arranged to drive the rod actuating means, and a power device acting on the lever said power device being secured to said housing.

7. A punching or riveting tool according to claim 6, in which the power device is an air motor having a hollow piston and piston rod.

8. A punching or riveting tool of the kind referred to, comprising a pair of jaws, a tubular member at one end of which the jaws are supported for relative movement, a rod guided within said tubular member and connected to one of said jaws, a housing movably engaged by the other end of said tubular member, means in said housing for actuating the rod to move said jaw relative to the other jaw, a coupling arranged between said tubular member and said housing and which is dislocatable to permit relative movement of said jaws towards and away from each other independently of the actuation of said rod, a lever pivoted in said housing and arranged to drive the rod actuating means, a power device acting on the lever said power device including a plurality of pistons and cylinders arranged to operate said lever in either direction, and means including a valve to control the operation of pressure medium in said cylinders.
